UNITED STATES PATENT OFFICE.

HUGH G. MACWILLIAM, OF NEW ROCHELLE, NEW YORK.

SUSPENDERS.

SPECIFICATION forming part of Letters Patent No. 755,026, dated March 22, 1904.

Application filed June 23, 1902. Serial No. 112,745. (No model.)

To all whom it may concern:

Be it known that I, HUGH G. MACWILLIAM, a subject of the King of Great Britain and Ireland, residing at New Rochelle, in the county of Westchester and State of New York, have invented certain new and useful Improvements in Suspenders, of which the following is a specification.

My invention relates to improvements in 10 suspenders of that class in which the shoulder-straps are connected with the rear trouser-tab by straps which have fixed connection with the shoulder-straps and slidale connection with the trouser-tab.

15 The invention consists in the features of construction and combination hereinafter more particularly described and claimed.

In the accompanying drawing, forming part 20 of this specification, the figure is a view of a back of a pair of suspenders embodying my invention, so much only of the shoulder-straps being shown as is necessary to illustrate the invention.

As shown in the drawing, the shoulder- 25 straps A and A' are independent of each other and are provided at their rear ends with links 2 and 2^a, respectively. The links 2 and 2^a are formed with eyes 3 and 4 and 3^a and 4^a, through which eyes are passed and secured the ends of 30 straps 5 and 6. The straps 5 and 6 are threaded intermediately and independently through the eyes 7 and 8 of the loop 9. To the loop 9 is secured the downwardly-projecting trouser-tab strap 10, formed at its ends with openings 11 to receive the rear trouser-buttons. As shown 35 in the drawing, the distance between the eyes

of the shoulder-strap loops to which the ends of the connecting-straps are secured is equal to the distance between the eyes of the trouser-tab, and the connecting-straps are crossed intermediately of the trouser-tab and shoulder-straps. 40

Having now described my invention, what I claim as new, and desire to secure by Letters Patent, is—

1. A pair of suspenders comprising the shoulder-straps, a trouser-tab, a double loop carried by said trouser-tab, and a pair of straps connected at their rear ends with the shoulder-straps, and intermediately and independently threaded through the eyes of said trouser-tab loop, said connecting-straps being separated an equal distance at their trouser-tab and shoulder-strap ends, as and for the purpose set forth. 50

2. A pair of suspenders comprising the shoulder-straps, a trouser-tab, a double loop carried by the trouser-tab, double loops carried by the rear ends of the shoulder-straps, the distance between the eyes of said trouser-tab loop being substantially equal to the distance between the eyes of each shoulder-strap loop, and a pair of straps independently connected at their ends to the eyes of the shoulder-strap loops, and intermediately threaded through the eyes of the trouser-tab loop. 60

In testimony whereof I affix my signature in presence of two witnesses.

HUGH G. MACWILLIAM.
